UNITED STATES PATENT OFFICE.

RICHARD ALBERT MINTERN, OF HORSHAM, VICTORIA, AUSTRALIA.

CULTIVATING IMPLEMENT.

1,221,565.

Specification of Letters Patent.

Patented Apr. 3, 1917.

Application filed September 28, 1916. Serial No. 122,662.

To all whom it may concern:

Be it known that I, RICHARD ALBERT MINTERN, a subject of the King of Great Britain, residing in Wilson street, Horsham, in the 5 State of Victoria, Commonwealth of Australia, have invented new and useful Improvements in Cultivating Implements, of which the following is a specification.

This invention relates to improvements in 10 cultivating implements and it has been devised in order to provide an implement which will be essentially suitable for surface cultivation and on land reasonably free from obstructions.

15 The invention, furthermore, embodies certain novel features of construction and arrangements of parts which serve to make the cultivator economical and highly efficient in use.

20 In order that the invention may be more readily understood reference will now be had to the accompanying sheets of explanatory drawings wherein:—

Figure 1 is a view in side elevation of a 25 cultivating implement constructed in accordance with the invention and showing the off side transport wheel removed.

Fig. 2 is a view in plan of Fig. 1 and shows part of the implement removed for 30 convenience of illustration.

Fig. 3 is a view in front elevation of Fig. 2.

Fig. 4 is a view in sectional front elevation of part of the implement frame taken on the dotted line *a—a* Fig. 2.

35 Fig. 5 is a view in plan of part of the frame of the cultivating implement and hereinafter is fully described.

In the drawings like characters of reference have been employed to indicate similar 40 or corresponding parts in the different views and the numeral 1 designates a stout axle beam of angle iron the ends of which are fitted with cranked stub axles 2 on which are mounted high transport wheels 3. The 45 stub axles 2 are secured removably to the ends of the beam 1 by means of collars 4 and bolts 5 or the like means. A frame 6 made of light angle iron and reinforcing bars 6¹ of the same material is pivotally 50 mounted on a rod 1² which is supported in jaws 6² fitted to the stout beam 1 at suitable points.

The central part of the axle beam 1 is furnished with a forwardly projecting beam 55 7 formed of one stout or two light angle iron bars and to the forward end of said beam

is fitted a casting 8 having a vertical boss 9 for accommodating the post 10 of steering wheels 11 of approved form. The axle beam 1 and the forwardly extending beam 7 form 60 a rigid T-shaped frame for supporting the operative parts of the implement. In lieu of employing a pair of steering wheels 11 as shown in the drawings I may use a caster wheel of ordinary design. 65

The rear end of the beam 7 is rigidly mounted on the center of the beam 1 and its forward end is stayed by diagonal bars 12 which are clamped to the said beam 1 at 13.

A vertical guide 15 is fitted to the center 70 of the front member of the frame 6 to retain the outer end of frame 6 in correct relation to the beam 7 and to permit of the forward part of the said frame 6 being raised and lowered as desired. The guide 75 15 is provided with stays 16 which insure rigidity to the structure under all ordinary working stresses.

A quadrant 17 is fitted to the beam 7 and a bolt 18 passing through the forward leg 80 of said quadrant pivotally supports a lever 19. The forward end of the lever 19 is connected by a link 20 to the forward part of the frame 6 and by operating said lever the forward end of said frame 6 can be raised 85 and lowered as and when required.

The lever 19 is furnished with a hand operated pawl 21 which is adapted to engage with the teeth of the quadrant 17.

The ends of the front bar of the frame 6 90 are fitted with depending brackets 22 which are designed to support the ends of a bar 23.

The forward ends of yoke-shaped sections 24 are pivotally mounted on the bar 23 and to the said sections are clamped a plurality 95 of tines 25 furnished with an approved form of share 26. The tines can be of the rigid type shown in Figs. 1, 2 and 3 (in dotted lines) or of the spring type if desired.

The tines are set in a zig-zag line so as to 100 insure wide spaces therebetween to provide for the free passage of weeds and other rubbish through the implement when the same is in operation.

A tine 25 is fitted to the bar 23 at the right 105 hand side of each section 24 and those tines constitute the forward row and are connected to the sections by suitable sides and rear ends of each of the sections 24 and tines forming a third row are clamped to 110 rearward extensions 24¹ disposed centrally on the said section.

It will be obvious that tines of various descriptions can be fitted to the sections and connected thereto in different ways and if preferred disks can be fitted to the sections of the cultivator and arranged in any approved way. The sections 24 can work separately or they can be made to work together by connecting their ends with rigid straps 24² (see Fig. 5).

- 10 Two or more standards 27 are fitted near to the back of the frame 6 and a transverse rod 28 is mounted in bosses formed on the upper ends of said standards. A lever 29 is fitted rigidly to the rod 28 and projects upwardly therefrom at an approved angle. An arm 30 projects rearwardly from the transverse rod 28 above the center of each section 24 and a link 31 connects the outer end of said arm to the section directly beneath. The lever 29 is provided with a hand operated pawl 32 which is adapted to be engaged by the teeth of a quadrant 33 fitted to the frame 6.
- 25 The lever 29 is operated to raise and lower the back ends of the sections 24 as desired and to facilitate the raising operation a strong tension spring 34 is arranged to exert a constant forward pull on the lever (see Fig. 1 of the drawings).
- 30 The lever 19 is also fitted with a compensating spring 35 and is operated to raise and lower the front end of the frame 6 and the corresponding ends of the sections 24.
- 35 The beam 1 is provided with a detachable seat 37 for the driver and the operating levers 19 and 29 are placed so as to be grasped conveniently by the driver when seated thereon.
- 40 The forward end of the beam 7 is adjusted on the post 10 of the steering wheels 11 by moving a collar 41 on said post to the position desired and then clamping it firmly by means of a set-screw 42.
- 45 A casting 43 is fitted to the top of the post 10 and secured adjustably within a boss 44 on said casting is one end of a bar 45. The said bar 45 is bent downwardly and has its opposite end secured by a bolt 50 to arms 46 projecting forwardly from the center of the boss surrounding the axle 47 carrying the steering wheels 11.

Diagonally disposed hauling bars 48 are secured to the beam 1 at their rear ends and their forward ends are connected to links 49 which pass forwardly and embrace the bar 45. A hook 50 is fitted to the forward end of the links 49 to engage the swingle tree to which the draft animals are coupled.

The levers 19 and 29 are fitted with detachable handles 52 which are removed and replaced with longer handles 53 when the implement is used in combination with a seed-drill, the object of which will be apparent to those skilled in the art.

What I do claim is:

1. A cultivating implement having a rigid T-shaped frame, a frame pivotally supported from said T-frame for supporting cultivating means, means for adjusting the free end of said pivoted frame with respect to said T-frame, a guide member carried by said pivoted frame and embracing the longitudinally extending part of said T-frame for bracing said pivoted frame against lateral stresses, and braces extending from the top of said guide to the sides of said pivoted frame at its free end.

2. A cultivating implement having a rigid T-shaped frame, a frame pivotally supported from said T-frame for supporting cultivating means, means for adjusting the free end of said pivoted frame with respect to said T-frame, a guide member carried by said pivoted frame and embracing the longitudinally extending part of said T-frame for bracing said pivoted frame against lateral stresses, said T-frame having a relatively wide cross part between the wheels and said pivoted frame being of substantially the same width as the T-frame whereby a large area may be cultivated at one passage of the implement, and a strap T fixed to the top of said guide member, the ends of which extend to the outer sides of said pivoted frame at its free ends and are fixed thereto, thereby forming braces for the pivoted frame.

In testimony whereof I affix my signature in presence of two witnesses.

RICHARD ALBERT MINTERN.

Witnesses:

JAMES H. ANDERSON,
MARGARET ROSSITER.
